UNITED STATES PATENT OFFICE.

WILBER F. TRUMBO AND WILBERT L. KIEFFER, OF NEW CARLISLE, OHIO.

OIL-FILTERING DEVICE.

Application filed June 25, 1923. Serial No. 647,714.

To all whom it may concern:

Be it known that WILBER F. TRUMBO and WILBERT L. KIEFFER, citizens of the United States of America, residing at New Carlisle, in the county of Clark and State of Ohio, have invented new and useful Improvements in Oil-Filtering Devices, of which the following is a specification.

The purpose of the invention is to provide a means for attachment to the slanting cover of the transmission housing of a conventional form of automobile, so that the oil transmitted to the transmission drums by the well known splash system must pass through the device so that carbon, lint, and other foreign matter finding its way into the lubricating oil may be trapped and easily removed upon the periodical removal or displacement of the cover of the transmission casing. It is further the object of the invention to provide a device of this character which is simple in construction, cheap to manufacture and durable and effective in operation.

With these general purposes in view the invention consists in a construction and combination of parts of which a preferred embodiment is shown in the accompanying drawings, wherein:

Figure 1 is a sectional view taken longitudinally through the transmission and crank case of an auto-vehicle, showing the position of the invention relative thereto, the invention being shown in elevation.

Figure 2 is an elevational view of the device comprising the invention.

Figure 3 is a section on the line 3—3 of Figure 2.

Figure 4 is a section on the line 4—4 of Figure 2.

Figure 5 is a section on the line 5—5 of Figure 2.

Figure 6 is a perspective view of the shield.

The invention comprises an open trap-
ezoidal-shaped frame 1, perforated as at 2
for the reception of fasteners 3 by means
of which the frame is secured to the cover
4 of the transmission casing 5. The frame
is designed to support a screen 6 of cross-
sectionally semi-circular form, the narrow
end of the screen being connected with a
plate 7 constituting the bottom of a reticu-
lated receptacle into which the oil is re-
ceived and passed to leave the sediment or

residue in the receptacle on the bottom of
which it is deposited by gravity, due to the
position of the device on the cover 3.

In order that the oil may be directed into
the reticulated receptacle in its passage from
the crank casing to the transmission drums,
a shield 8 is provided and secured to the
frame 1 at the upper end of the reticulated
receptacle, said shield being preferably of
sheet metal formed with a rolled or coiled
edge 9 at one side, being cut away at the
other side as indicated at 10 to provide a
space, together with the open space at the
top, for the entrance of oil as it is thrown
in the movement of the fly wheel, the rolled
or coiled edge 9 constituting a wing serving
to catch the oil and deflect it into the reticu-
lated receptacle from which it passes to the
transmission drums, the foreign substances
contained in the oil as a result of the opera-
tion of the engine being retained in the re-
ceptacle for disposal when the cover 4 is
removed from the transmission casing.

Aside from this advantage of providing
a means for directing the oil in the operation
of the splash system on to the transmission
drums, the invention also serves as a means
to prevent damage to the motor which may
occur from time to time due mostly to
foreign matter such as carbon, lint, and the
like finding its way into the lubricating oil.

Having described the invention, what is
claimed as new and useful is:

1. The combination with a transmission
case having an opening and a cover for the
opening, of a frame conforming to and
fitting in the opening of said case and se-
cured to the under face of the cover, a reticu-
lated transversely arcuate receptacle secured
to the frame under said opening, a plate
at one end of the receptacle constituting a
bottom for the receptacle into which the
oil is received and passed to leave the sedi-
ment in the receptacle on the bottom of
which it is deposited by gravity due to the
position of the receptacle, and a shield pro-
vided at and secured to the opposite end of
the receptacle, one side of the shield being
cut away causing a space to be formed for
the entrance of oil as it is thrown in the
movement of the fly wheel, the opposite side
of the shield having a rolled edge opposite
said space and constituting a wing inclined
over toward the transmission mechanism,
serving to catch the oil and deflect it into

the receptacle which overlies, covers and passes the oil over entirely all of the transmission drums.

2. The combination with a transmission case having an opening and a cover for the opening, of a frame conforming to and fitting in said opening of said case and secured to the under face of the cover, said frame having an opening of slightly less size than and substantially conforming to the opening in the case, a reticulated transversely arcuate receptacle connected to and carried by the frame and dependingly covering the opening in said frame, the receptacle being of a shape corresponding to and fittingly depending through the opening formed in said case, a plate at one end of the receptacle constituting a bottom for the receptacle into which the oil is received and passed to leave the

sediment in the receptacle on the bottom of which it is deposited by gravity due to the position of the receptacle, and a shield provided at and secured to the opposite end of the receptacle, one side of the shield being cut away causing a space to be formed for the entrance of oil as it is thrown during the movement of the fly wheel, the opposite side of the shield having a rolled edge constituting a wing inclined over toward the transmission mechanism, serving to catch the oil and deflect it into the receptacle which overlies, covers and passes the oil over entirely all of the transmission drums.

In testimony whereof they affix their signatures.

WILBER F. TRUMBO.
WILBERT L. KIEFFER.
